Primary Examiner—Alan P. Douglas*Assistant Examiner*—Rob Spear*Attorney, Agent, or Firm*—Watts, Hoffmann, Fisher & Heineke[57] **CLAIM**

The ornamental design for a mesh panel, as shown and described.

DESCRIPTION

FIG. 1 is a detail perspective view of the top left portion of the mesh panel of FIG. 4, showing my new design. The figure is shown at an enlarged scale for ease of disclosure; FIG. 2 is an edge view of the mesh panel, taken from either side of the panel;

FIG. 3 is a section of the panel sectioned along the line III—III of FIG. 4; and,

FIG. 4 is an elevational view as seen from either the front or the rear thereof;
